UNITED STATES PATENT OFFICE.

CHARLES J. NASH, OF CHICAGO, ILLINOIS, ASSIGNOR TO UNIVERSAL DRAFT GEAR ATTACHMENT CO., OF CHICAGO, ILLINOIS, A CORPORATION OF ILLINOIS.

DRAFT-RIGGING.

1,143,303.

Specification of Letters Patent. Patented June 15, 1915.

Application filed September 23, 1914. Serial No. 363,064.

To all whom it may concern:

Be it known that I, CHARLES J. NASH, a citizen of the United States, and resident of Chicago, county of Cook, and State of Illinois, have invented certain new and useful improvements in Draft-Rigging, of which the following is a specification, and which are illustrated in the accompanying drawings, forming a part thereof.

10 The invention relates to draft rigging for cars, and particularly adapted for use on comparatively light cars such as are in service in subways and on interurban lines.

15 The objects of the invention are to provide a simple construction, and improved means for securing pivotal relation between the coupler and the gear.

20 The features of the invention are herein-after pointed out in connection with its description, and an embodiment of it is illustrated in the accompanying drawings, in which—

25 Figure 1 is a detail longitudinal vertical section of a car taken on the center line of draft; Fig. 2 is a detail plan view, partly in section, of the draft rigging; Fig. 3 is a view in perspective of the yoke or coupler extension; Fig. 4 is a transverse sectional view on the line 4—4 of Fig. 2; Fig. 5 is a 30 view in perspective of the follower; and Fig. 6 is a view in perspective of one of the draft plates.

35 The center sills of the car are represented at 10, 11, and are shown as being united by a cover plate 12 and as carrying a box-like draft sill 13, the side walls of which are riveted to the center sills, its bottom 14 forming the means of attachment of the draft rigging. These features are not novel.

40 The draft plates 15, 16, are alike except that they are made as rights and lefts. Each is provided with a vertical wall having at its upper edge a flange 17 which extends outwardly and inwardly and bears against and 45 is riveted to the bottom 14 of the draft sill. At its inner end the draft plate is provided

50 with an instanding shoulder 18, which extends to the center line of draft and at its inner edge has a vertical rearwardly-extending flange 19. The flange 17 extends backwardly to the rear end of the flange 19, with which flange it is integrally united. The two draft plates are secured together by 55 means of rivets 20 set through their flanges 19, and also by means of a bottom tie-plate

21 riveted to outstanding bottom flanges 22. The draft plates are provided with such external ribs and fillets as may be deemed essential to strength. At the forward end each draft plate is provided with instanding draft lugs 23, 24, for engagement by a forward follower, these lugs being vertically aligned and spaced apart to accommodate the yoke or coupler extension, as hereinafter described.

60 The butt 25 of the coupler is horizontally slotted from its inner end to receive the yoke, and is rounded to permit it to turn freely upon the follower. The yoke or coupler extension, designated as a whole by the 70 numeral 26, is shown as in the form of a continuous loop having parallel side members 27, 28, and a flat rear end 29 which is preferably extended upwardly and downwardly to increase the bearing surface for 75 the cushioning element and the buffing shoulders. The forward end 30 of the yoke is rounded and adapted to fit within the slot of the coupler butt, and is slotted, as shown at 31, to receive a pivot pin 32 for uniting 80 it with the coupler.

85 Each of the draft plates 15, 16, is provided with an instanding longitudinal ledge 33, upon which, and the lower draft lugs 24 the side members 27, 28, of the coupler extension rest and slide. To facilitate assembling the forward end of the ledge 33 terminates some distance from the draft lug 24, the upper face of which is in effect a continuation of the ledge. A single follower 90 is employed, and takes the form of a plate 34 having near its upper and lower edges laterally projecting wings 35, 36; the upper wings resting and sliding upon the side members 27, 28, of the coupler extension. 95 The forward face of the follower is provided with a boss 37, having a concave face to receive and form a bearing for the end of the coupler butt. The curvature of the end of the coupler butt is concentric with the 100 pivot pin 32.

105 The cushioning mechanism may be of any preferred form. There is shown in the drawings at 38 a common type of Westinghouse friction draft gear, and the other elements of the device are shown as especially designed for its accommodation. The rear end of the cushioning mechanism bears against the rear end of the coupler extension, and its forward end against the fol- 110

lower plate 34. In draft the cushioning mechanism is compressed by the forward movement of the coupler extension, the stress being transmitted to the car through the lugs 23, 24. In buff the follower plate 34 is pushed inwardly by the coupler, compressing the cushioning mechanism, the stresses being transmitted through the rear end of the coupler extension and the shoulders 18.

The coupler is free to oscillate about the pin 32, its end turning in the concave face of the boss of the follower, and the pin 32 travels backwardly in the slot 31 of the yoke in buffing.

I do not desire to be limited to the particular design or details of the device as illustrated in the drawings, the invention being of the scope defined in the following 20 claims:

1. In a draft rigging, in combination, a coupler having its rear end horizontally slotted, a pin set vertically through the coupler and crossing the slot therein, and a 25 coupler extension in the form of a continuous loop for inclosing shock-absorbing ele-

ments, the forward end of the loop entering the slot of the coupler and inclosing the pin.

2. In a draft rigging, in combination, a coupler having its rear end horizontally slotted, a pin set vertically through the coupler and crossing the slot therein, a coupler extension in the form of a continuous loop for inclosing shock-absorbing elements, the forward end of the loop entering the slot 30 of the coupler and being provided with a longitudinal slot through which the pin passes.

3. In a draft rigging, in combination, a coupler having its rear end horizontally slotted, a pin set vertically through the coupler and crossing the slot therein, a coupler extension in the form of a continuous loop for inclosing shock-absorbing elements, the forward end of the loop entering the slot of the 40 coupler and having a longitudinal slot opening through its inner face and within which the pin is located.

CHARLES J. NASH.
